ELECTRIC SOLDERING APPARATUS

George Louie Ward, Northwood, England, assignor to Standard Telephones and Cables Limited, London, England, a British company

Application June 10, 1943, Serial No. 490,247
In Great Britain June 19, 1942

4 Claims. (Cl. 219—12)

This invention relates to electric soldering apparatus. In my application Serial No. 424,231, filed Dec. 24, 1941, I have described and claimed a form of foot operated soldering apparatus (thus leaving both hands free for manipulation of the soldering operation) which is adapted for use with any size of work or in any location.

It is the object of the present invention to provide a soldering apparatus which is somewhat more robust than the forms of apparatus described in the above mentioned specification.

According to the present invention I provide electric soldering apparatus comprising an overhanging support adapted to be mounted on a bench and an electric heater or an electrically heated bit fixed to a plunger moveable vertically in said support so as to be brought down and removed from work to be soldered.

Preferably the electric heater or electrically heated bit is operated by means of a treadle, thus leaving both hands free for manipulation of the soldering apparatus.

Preferably also the overhanging support is made of two mutually insulated portions which construction allows of the apparatus being adapted for use in several different ways, as will be clear from the following description.

The nature of the invention will be better understood from the following description of one embodiment thereof taken in conjunction with the accompanying drawings in which:

Fig. 1 is a side view of the embodiment;

Fig. 2 is a plan view; and

Fig. 3 is a sectional view of the head of the apparatus.

Referring to the drawings, a curved arm 3 is supported on base plate 1 which in turn is adapted to be fixed by screws 4 to a work bench 2. The curved arm 3 resembles in shape that commonly used to support a drill or other similar vertically mounted machine tool, but is split longitudinally into two portions 3a and 3b insulated from one another. These portions are cast integrally with portions 5c and 5d respectively resting on the base plate 1, and are made of electrically conducting material. Terminals 6a and 6b for attachment of cable lugs are mounted externally of the two portions 3a and 3b of the arm, and terminals 5a and 5b are mounted on the portions 5c and 5d. The terminals 6a and 6b are mounted on a bolt 8 on which is an insulating washer 7 separating the two portions 3a and 3b of the arm. An insulating bush 9 fits over the bolt 8 to insulate the portion 3a of the arm from the bolt.

The flat base portions 5c and 5d of the arm 55

portions 3a and 3b are secured to the conducting base 1, with the interposition of an insulating plate 11.

The portion 3a of the arm 3 ends in a circular boss 10 inside which fits a bush 12 held therein by screws 13. This bush 12 is slotted for entrance of a Bowden cable 14 which passes from the underside of the bench 2 and in a slot in the inner side of the portion 3a of the arm. The outer sheath of the Bowden cable 14 is secured in several places in the said slot and to bush 12. A plunger 17 is a sliding fit inside the bush 12 and a cap 18 is attached to the upper end of the plunger 17. The inner wire 15 of the Bowden cable 14 is secured by a nut 16 to the cap 18. A coil-spring 19 is held between the cap 18 and the bush 12. A soldering tool (not shown) can be held in the plunger 17 by means of a screw 20 (Fig. 1). A covering 50 fits over the upper part of bush 12 and plunger 17 and rests on boss 10.

The inner wire 15 of the Bowden cable passes through the bench 2 and is secured to a nipple 21 which screws into a connecting collar 22. A rod 23 screws into the connecting collar 22 and passes into a barrel 24 and is held by a set screw 25. The extent to which the rod 23 is within the barrel 24 is adjustable in accordance with the height of the bench 2 above the ground.

A rod 26 passes into the barrel 24 and carries a collar 28 between which and a cap 28 is a coil spring 30. The rod 26 is secured to a shackle 27 secured in turn to a treadle 31. The treadle 31 is pivoted at 34 and carries an arm 35 provided with a stop member 36. The stop member 36 is held against a fixed stop 37 by a spring 33 attached to the treadle 31 and a base plate 32. The position of the stop 36 in the arm 35 is adjustable as is also the position of the fixed stop 37. The positions of the stops 36 and 37 are adjustable in accordance with the height of the tool secured in plunger 17 above the bench 2. An electric switch 40 is secured to base plate 32 in such position that when the tool is brought down on to the work to be soldered stop member 36 just touches a switch plunger 39. A further depression of the treadle then compresses spring 30 and causes stop 36 to actuate switch plunger 39 to close the switch.

The positions of switch 40 and the fixed stop 37 in relation to the stop 36 may be reversed, the switch 40 being then arranged so that pressure on the plunger 39 opens the switch. In this case the switch 40 would be closed soon after the movement of stop 36 with the treadle had commenced and a positive limitation to the extent to which

plunger 17 could be depressed would be provided. The particular arrangement to be used depends upon the character of the soldering operation to be performed.

The electrical connections to the apparatus vary according to the form of tool to be fixed in the plunger 17 and the construction described is such that various forms of tools may be used. The base plate is provided with three terminals 41, 42 and 43 to any two of which the conductors from an external supply may be connected. The outer terminals 41 and 43 are insulated from the base plate 1 whilst the middle one 42 is electrically connected thereto. In the drawings the outer terminals 41 and 43 are shown connected by straps 44 and 45 to terminals 5b and 5a and in such case of course the external electric supply is connected to terminals 41 and 43. The terminals 6a and 6b are then connected by short lengths of flexible cable to the terminals of an electrical heater for the soldering tool.

The electrical heater may take the form of a split carbon cylinder the two halves of which are mounted in an insulating manner in plunger 17 and adapted to be bridged by the work to be soldered (usually of circular form). When this split carbon cylinder is brought down on to the work the latter forms an electric connection between them and when switch 49 is closed the current flows, the carbon then serving as a heater.

Another form of soldering tool which may be used is a plain carbon rod. When this is secured in plunger 17 the electrical connections are such that the external supply is connected to the terminal 43 and to terminal 42. As stated above terminal 42 is connected to base plate 1. Strap 44 is removed. The electric circuit is then completed between the carbon rod and the work to be soldered.

Although the portion 3a of the arm 3 is conducting and thus serves as an electrical connection from terminal 5a to the carbon rod mounted in plunger 17, the electrical connection between plunger 17 and the bush 12 may not be a very good one and it is preferred also to connect a short length of flexible cable between the terminal 6a and the carbon rod mounted in plunger 17.

The tool mounted in plunger 17 may also take the form of a copper bit heated by means of a wound form of heater or by means of two carbon rods. The terminals of the wound heater or of the carbon rods are connected by short lengths of flexible cable to terminals 6a and 6b.

The base plate 1 is provided with a groove or grooves 46 in which may be clamped holders for a body to be soldered.

The plunger 17 may be used as a pressure medium upon or as a conducting bridge between two portions of a body mounted insulatingly upon the base 1, the terminals 41 and 43 being then connected by flexible cables with the respective portions.

What is claimed is:

1. An electric soldering apparatus comprising

means for holding a work piece, means for receiving at least one electric heating element, means for moving the receiving means with respect to the holding means to approach and separate said heating element and said work piece, a structure supporting the receiving means, means for supplying electric current to said heating element in two insulated electric paths forming part of said structure, means for supplying current to a third electric path including the holding means so as to connect selectively either said two electric paths through said work piece, or one of said two electric paths through said work piece with the third electric path.

2. An electric soldering apparatus comprising means for holding a work piece, means for receiving at least one electric heating element, means for moving said receiving means with respect to said holding means to approach and separate said heating element and said work piece, a structure supporting the receiving means, and comprising two insulated arms one of which carries the receiving means, means for supplying electric current to said heating element through said arms, means for supplying current to a third electric path including said holding means so as to connect selectively either said two electric paths through said work piece, or one of said two electric paths through said work piece with the third electric path.

3. An electric soldering apparatus comprising a holder for a work piece attached to a base plate, a plunger for receiving at least one electric heating element, means for moving said plunger with respect to said holder to approach and separate said heating element and said work piece, a structure attached to said base plate attached mechanically to, but insulated electrically from, said base plate and supporting said plunger, means for supplying electric current to said heating element in two insulated electric paths forming part of said structure, means for supplying current to a third electric path including said base plate and said holder so as to connect selectively either said two electric paths through said work piece, or one of said two electric paths through said work piece with said third electric path.

4. An electric soldering apparatus comprising means for holding a work piece, a plunger receiving at least one electric heating element, means for moving said plunger with respect to the holding means to approach and separate said heating element and said work piece, a structure supporting said plunger and comprising two insulated arms one of which carries said plunger, means for supplying electric current to said heating element through said arms, means for supplying current to a third electric path including said holding means so as to connect selectively either said two electric paths through said work piece, or one of said two electric paths through said work piece with the third electric path.

GEORGE LOUIE WARD.
